UNITED STATES PATENT OFFICE.

SAMUEL MITCHELL, OF DETROIT, MICHIGAN.

STATION INDICATOR.

1,414,369.

Specification of Letters Patent. Patented May 2, 1922.

Application filed June 30, 1920. Serial No. 392,923.

To all whom it may concern:

Be it known that I, SAMUEL MITCHELL, a citizen of the United States, residing at Detroit, in the county of Wayne and State 5 of Michigan, have invented new and useful Improvements in a Station Indicator, of which the following is a specification.

Experience has demonstrated that a practical electromechanical station indicator requiring little attention from persons in authority is a desideratum. This will be better appreciated when it is stated that it is extremely difficult for passengers in street cars, especially at night, to identify the crossings 10 or stops or stations as the same are approached by a car and hence it frequently happens that passengers are carried beyond their respective destinations and are subjected to the annoyance of walking back to 15 such destinations or else are caused to leave the car at points unknown to them which makes it difficult for them to find their respective ways.

The object of my present invention, therefore, 20 is the provision of an electro-mechanical station indicator that will accommodate itself to different speeds of a car, that will be susceptible of use on all kinds of cars, that will be adapted, with slight adjustment, 25 for use on those lines in which the cars traverse the same course "out" and "in" as well as those lines known as "belt" lines in which the cars traverse a continuous course from and to a common point, and 30 that will be capable of utilizing the car-driving current for rewinding the web at the commencement of a belt line run.

To the attainment of the foregoing, the invention consists in the improvement as 40 hereinafter described and definitely claimed.

In the accompanying drawings, hereby made a part hereof:—

Figure 1 is a front elevation of a station indicator constructed in accordance with 45 my invention, with the face plate of the casing removed.

Figure 2 is a view similar to Figure 1 but with certain elements omitted for the clearer illustration of other elements.

Figure 3 is a detail elevation of driving connections and control provisions herein-after explicitly referred to.

Figures 4 and 5 are detail sections taken in the planes indicated by the lines 4—4 and 55 5—5, respectively, of Figure 3.

Figure 6 is an enlarged end elevation of

the indicator showing the knife-switch and the rheostat comprised in my improvement.

Figure 7 is a transverse section on an enlarged scale, taken in the plane indicated by 60 the line 7—7 of Figure 1, looking toward the right.

Figure 8 is a front elevation of the station indicator complete on a greatly reduced scale.

Figure 9 is a detail enlarged view of one of the terminals to supply current at appropriate points before the car reaches a crossing for the actuation of the web bearing the names of stations—i. e., crossings or 70 stops; it being understood in this connection that car-moving current is not utilized under normal working conditions to move the web step by step, and that the web is moved a predetermined distance as the car 75 approaches a station to display the name of the station so that a passenger may, if necessary, have ample time to signal for the car to stop at said station.

Figures 10 and 11 are diagrammatic views 80 designed to exemplify the operation of the apparatus as described.

Similar numerals of reference designate corresponding parts in all of the views of the drawings.

A detailed description of one of the current-supply terminals alluded to will suffice to impart a definite understanding of all. Referring therefore particularly to Figure 9 it will be understood that 1 is a hanger, 90 appropriately supported adjacent to the hanger 2 of a trolley wire 3, and equipped with a conductive terminal 4, in the form of a rod of suitable length and designed to be connected with a source of electric energy 95 of a character suitable for the step by step movement of the web of the indicator. It will also be observed that the trolley pole 5 carries the usual wheel 6 for co-operation with the wire 3 to supply current to the car 100 motor, and also carries a circumferentially-grooved wheel 7 for co-operation with the rod 4 to supply current for a certain period of time to the motor 8 of the station indicator as the car approaches a station.

The novel station indicator is designed to be carried at any preferred point in a car, and it is within the purview of my invention to construct the parts of the indicator of various materials most appropriate and 110 as light as possible consistent with strength, durability and reliability in operation.

In addition to the motor 8, the station indicator includes a casing body 9 and front wall 10 complementary thereto; the said front wall 10 being preferably, though not necessarily, removable to afford access to the interior parts, and being provided with a preferably glazed display opening 11, Figure 8. On one end wall of the casing body 9, Figures 1, 2, 6 and 8 I employ a rheostat 12 and a knife switch 13. These elements per se may be and preferably are of the ordinary constructions well known in the electrical art and need not therefore, be described in detail. The interior of the casing body 9 is divided by a transverse wall 14 into two compartments 15 and 16 in the latter of which the motor 8 is located. For convenience of description I will hereinafter designate the compartment 15 as the web compartment and the compartment 16 as the motor compartment. In the web compartment 15 I arrange one or more (preferably two) incandescent lamps 17. These are preferably disposed in the ordinary well known lighting system of an electric car and need not be further described except to say that they are subject to a switch by the manipulation of which current may be supplied to or cut off from their filaments. Also arranged in the compartment 15 is a web 18, preferably of translucent character, that bears in regular sequence the station names, and is disposed in front of a guide member 19 mounted between the partition wall 14 and the outer end wall 20 of compartment 15. Fixed to and extending longitudinally inward from the end wall 20 are tubular projections 21, Figure 2, and opposed to the inner ends of tubular journals 21^a on said projections 21 are disks 22 which are connected to and retained in position by retractile coiled springs 23, housed in the projections and journals. It will also be noted that metallic brackets 24 are preferably associated with the projections 21, said brackets 24 being fixed to the back wall of the casing body 9 and the projections 21, and being spaced from the latter. Mounted in the opposite end of the web chamber 15, with reference to the projections 21 and journals 21^a, are rotary circumferentially grooved disks 25 and 26, Figure 1, having central lugs 27. At 28 and 29, Figure 7, are the rolls complementary to the web 18; each of said rolls comprising a cylindrical body and heads, and each having in its body adjacent to one end a recess 30 in which is a short rod section 31. The web 18 is connected to the bodies of the rolls 28 and 29 but the recess 30 and the rod section 31 of each roll are left uncovered when the web is entirely removed from said roll. It will also be noticed here that near the points at which the ends of the web are connected to the cylindrical bodies of the rolls 28 and 29 the web is pro-

vided with lengthwise arcuate, thin metallic plates 32, each of which is designed to cover the adjacent recess 30 and rod section 31 as soon as a small portion of web is taken up on the roll. Each roll 28 and 29 is provided at one end with a tubular portion 33 to receive one journal portion 21^a and the cap 22 thereon, and each roll is provided in its opposite end with an angular socket to receive one of the lugs 27. Thus it will be manifest that either of the rolls may be positively rotated to take the web 18 thereon as the web is let off the other roll. An endless band 35 is mounted on and connects the circumferentially-grooved disks 25 and 26. Those end portions of the rolls provided with the recesses 30 and the rod sections 31 are arranged adjacent to the partition wall 14, Figure 7, and also arranged in the web compartment 15 and adjacent to and in parallelism with said partition wall 14 is a curvilinear lever 36, fulcrumed at 37^a and having its end portions superimposed upon springs 38 which yieldingly hold said end portions against upward movement. Slidable on the arms of the lever 36 and yieldingly held against outward movement by retractile springs 37 are bodies 38' on which are anti-friction wheels 39, designed when permitted to move upwardly into the recesses 30 of the rolls, to be moved outwardly on and endwise of the lever 36 by the tappet or rod sections 31. The end portions of the lever 36 and the parts complementary to said lever are arranged between guide plates 40, two pairs of which are employed. Connected to the movable bodies 38' are cables 41, 41^a, which are carried about vertical anti-friction rollers 42 and longitudinally through apertures 43 in the partition 14 and into the motor compartment 16. It will be noticed here that when almost all of the web 18 is off one roll, as appears at the left of Figure 7, the rod section 31 of that roll will press its complementary body 38' outwardly and will draw the cable belonging to said body. This provision has to do with the reversing of the feed of the web 18 when the end of a line is reached as will be hereinafter more fully set forth.

The circumferentially-grooved disk 26 is fixed to a longitudinal shaft 44, journaled in the partition wall 14, and also fixed to the said shaft 44 and arranged in the motor compartment 16 is a circumferentially-grooved pulley 45 that is connected by an endless band 46 with a circumferentially-grooved pulley 47, Figure 1. Said pulley 47 is fixed to and rotates with a spur-gear 48 alongside the same, and said spur gear 48 is intermeshed with a spur gear 49. Fixed to and rotatable with said spur gear 49 is a circumferentially-grooved pulley 50. This latter is connected by an endless band 51

with the circumferentially-grooved portions 52 of a rotatable body 53 having clutch faces 54 and 55. The body 53 is loose on a longitudinal shaft 56, and on said shaft 56 are miter gears 57 and 58 having clutch faces opposed to the clutch faces 54 and 55, respectively. One of said gears is loose on and the other is fixed to the shaft. It is to be noted here that the disk 25 is rotated solely by the band 35 and that there is no connection through the partition wall 14 between the miter gear 57 and said disk 25. Also fixed on the shaft 56 to always turn therewith are a spur gear 59 and a circumferentially-grooved pulley 60; the latter being connected by an endless band 61 with a circumferentially-grooved pulley 62 on the armature shaft 63 of the motor 8. Loosely mounted on a stub shaft carried by the adjacent side wall of the casing body 9 is a miter gear 64, interposed between and intermeshed with the gears 57 and 58. Fulcrumed at an intermediate point of its length near the back wall of the casing body 9, as indicated by 65, is a lever 66 on one arm of which is a gudgeon 67, disposed in a circumferential groove 68 of the body 53. To the other arm of said lever 66 is directly connected the before mentioned cable 41, Figures 2 and 7. The other cable 41^a after being carried around an anti-friction roller 67^a on the back wall of the casing body 9 is also connected to such other arm of the lever 66. It will also be noticed here that there is a rod connection 70 between the mentioned arm of the lever 66 and the knife or lever of the knife switch 13.

From the construction thus far described it will be understood that with the motor 8 supplied with current at intervals the web 18 will be moved step by step from one roll to the other, and when the end of a route is reached the driving connection from motor to the disk 26 will be reversed so that on the return movement of the car the web 18 will be moved step by step in reverse direction.

Intermeshed with the spur gear 59 on the longitudinal shaft 56 is a spur gear 71, Figures, 1, 2, 3 and 5. Said gear 71 is loose upon and eccentric to a longitudinal shaft 72, being arranged around an eccentric cam 73. The eccentric cam 73 is fixed to the shaft 72 and is utilized to adjust or position the gear sectors 74, hereinafter described. Carried by and arranged at the outer side of the spur-gear 71 are opposite spur-gear sectors 74. Fixed to the spur-gear 71 and the gear sectors 74 and arranged at the opposite side of said sectors 74, with reference to the gear 71, is a disk 75 in the periphery of which are opposite notches 76, Figure 4. The portion of the cam 73 at the inner side of the spur gear 71 is provided with a forwardly extending crank arm 77, and inter-

posed between said arm 77 and a forwardly-extending rod 78 on the back wall of the casing body 9, Figure 4, is a retractile spring 79, the function of which is to yieldingly hold the arm 77 in and return it to the relative position shown in Figure 4.

Located in a housing 80 adjacent to the back wall of the casing body 9 is a pair of electro-magnets 81, and complementary to said magnets 81 is an armature 82, pivoted at 83 and having a forwardly extending arm 84, movable in a slot 85 in the forward wall of the housing 80.

Fixed to and extending forwardly from the back wall of the casing body 9 is a bracket 86, Figures 3 and 4, and fixed to and extending laterally from said bracket 86 is a spindle 87, Figures 3, 4 and 5. Loose on the said spindle 87 is an eccentric cam 88, having a head 89 at its outer end on which is a radial arm 90. Said arm 90 is connected by a cable 91, Figure 4, with the arm 84 of armature 82, and is also connected to one end of a retractile spring 92 the other end of which is connected to the back wall of the casing body 9. The long eccentric cam 88 is disposed in a sleeve 93 at the outer side of and fixed to a spur gear 94, Figure 3, disposed between the spur gear 71 and the disk 75, and adapted in one position to be intermeshed with the sector gears 74. Thus when the magnets 81 are energized the gear 94 will be moved into position for cooperation with the sector gears 74, and when the magnets 81 are de-energized the spring 92 will function to move the gear 94 out of said position.

For cooperation with the notched disk 75 I provide a detent lever 95, Figures 3 and 4, and for cooperation with the spur gear 94 I provide the spur gear 96, Figures 3, 4 and 5. The detent lever 95 is normally held in yielding manner against the disk 75 by a retractile spring 97 interposed between the lever and the back wall of the casing body 9. Said lever 95 is also transversely apertured at 98 for the passage of a cable 99 that is extended loosely through an eye 100, Figure 6, in one end wall of the casing body 9 and is connected to the lever 101 of the rheostat 12. The cable 99 passes from the aperture in the detent lever 95 through a guide 102 on the back wall of the casing body 9 and is then wound about a drum 103. At its inner end the drum 103 is provided with a flange 104, notched at diametrically-opposite points, as indicated by 105. The gear 96 and the drum 103 are fixed to a shaft 106 on which is fixed an arm 107 between which and the back wall of the casing body 9 is interposed a retractile spring 108. The cable 99 is connected to said arm 101. Arranged between the gear 96 and the drum 103 is a spur gear 109, aligned and intermeshed with the spur gear 130

71. The shaft 106 extends loosely through the spur gear 109.

The arm 77 on the eccentric cam is connected to a cable 110. This cable 110 is 5 carried through a guide 111 on the back wall of the casing body 9 and is connected to the inner arm of the lever 66, Figures 3 and 4.

When my novel station indicator is to be 10 used on a car that traverses a route in one direction from end to end and then in the opposite direction from end to end, the rod 70 and the cable 110 are disconnected from the lever 66 and the indicator is operated 15 in the manner before described; the motor 8 being supplied with current at intervals in the manner hereinafter described.

It will be observed that the knife switch 13 is electrically connected with the collector 20 7 for collecting current to actuate the indicator; also, that a snap or other appropriate switch 112 is provided to interrupt the supply of current from the collector 7 when desirable or necessary. It will further be 25 observed that the rheostat 12 and the motor 8 are electrically connected with the knife switch 13, and that said knife switch is electrically connected with the source of 30 energy for driving the car motor, this latter provision being made for the rewinding of the web from one roll to the other precedent to commencing a run on a belt line.

When my novel indicator is used in the manner described on a car to move to and 35 fro on a line, the main lever 66 is adapted to be easily moved in the manner and for the purpose set forth.

On a belt line the indicator is designed to be used in the same manner with the exception that when the indicator is reversed the eccentric lever is actuated and throws certain parts of the mechanism out of gear and closes the switch when current from the car will be utilized to effect the rewinding.

45 When the rewinding is accomplished the clutch is reversed and in consequence the mechanism is put back in gear.

As is well known cars move in city limits at a lower rate of speed than in the suburbs 50 or country, and manifestly current will be collected for a longer period when the car is running slow than when the car is running fast. This condition is met and undue movement of the web at any time is averted 55 by the provision of my novel safety electro-magnet and complementary armature relatively arranged and connected as shown and described, and designed to operate in conjunction with the motor 8. It will be under-

60 stood in this connection that when energized the safety electro-magnet closes the second eccentric lever against the cam shaft and actuates the rheostat to diminish the speed of the motor 8 until the cam follower falls 65 into the cam slot. This allows the display

of only one station due to stopping of the motor 8. On the stopping of the motor 8, the safety electro-magnet holds the rheostat down until the current is cut off from the safety electro-magnet when the de-energization of the safety electro-magnet will be attended by return of the rheostat to its normal condition ready to assure the display of the name of the succeeding station.

In the event of trolley trouble or when 75 it is desired to send the car over a line to which the indicator is not suited, the indicator is electrically isolated from the current collector. This isolation is also effected when current from the car is utilized to rewind the 80 web on a belt line car at the commencement of a run.

The rolls and the web of my improvement are susceptible of being readily placed in and removed from the casing body 9. 85 From this it follows that the indicator may be readily made ready for the particular route over which a car is to be sent.

By particular reference to Figures 10 and 11 it will be understood that in the practical 90 use of my improvement current passes from the collector wheel to the motor 8 and the magnet 81 at the same time. This has the effect of rotating the disk 75 in the direction of the arrow which will cause the 95 element 95 to rock out of the notch 76 and take up slack of the cable 99. The disk 75 continues to revolve, and the gear sector 74 will then mesh with the gear 94 which was drawn over at the time that the motor 8 100 started to revolve. The sector 74 revolves the gear 94, in turn, through the gear 96, revolves the drum 103 against the tension of the spring 108 and pulls the lever of the rheostat downwardly and slows up the motor 105 8 by the time that the arm 101 reaches the last contact in the rheostat. The lever 95 is secured in the notch 76 which slackens the cable 99 sufficiently to allow the arm 101 to fall between the two contacts on the rheostat which stops the motor at the proper time to display the name of a street, but it

will be observed in this connection that the current is still supplied to the magnets 81 (due to the slow speed of the car in a city) and when the collector wheel runs off the wire the spring 92 serves to move the gear 94 from engagement of the sector 74, and the spring 108 throws the rheostat lever back to normal position ready for another street. 110 The overhead contact wire 4 is sufficiently long to complete the above operation when the car is running at the greatest rate of speed.

I have entered into a detailed description 125 of the construction and relative arrangement of the parts embraced in the present and preferred specific embodiment of my invention in order to impart a full, clear and exact understanding of said embodiment. I 130

do not desire, however, to be understood as confining myself to the said specific construction and relative arrangement of parts inasmuch as in the future practice of my invention various changes or modifications in the form and arrangement of parts may be made as fairly fall within the scope of my invention as defined in my appended claims.

Having described my invention, what I claim and desire to secure by Letters-Patent, is:—

1. An electro-mechanical station indicator having a web bearing the names of stations, electro-mechanical means to move the web, and means to supply the electro-mechanical means with current at intervals in the traverse of a car and comprising automatic means to assure uniform actuation of the indicator irrespective of the speed of the car, said automatic means including a rheostat and an electro-magnet.

2. An electro-mechanical station indicator having a web bearing the names of stations electro-mechanical means to move the web, including a clutch, and an organized mechanism controlled by the web-moving means to throw the clutch, and means to supply the electro-mechanical means with current at intervals in the traverse of a car and comprising automatic means to assure uniform actuation of the indicator irrespective of the speed of the car.

3. An electro-mechanical station indicator comprising a web bearing the names of stations, rolls complementary to the web and having tappet means exposed by unwinding of the web from the rolls, movable devices operable by said tappets when exposed, a driving connection for the rolls including a shiftable clutch member, a spring-pressed lever on which said movable devices are mounted and movable, springs connected to said movable devices, and means connecting the said movable devices and the shiftable clutch member, electro-mechanical means connected with said driving connection to actuate the same, and means to supply the electro-mechanical means with current at intervals in the traverse of a car and comprising automatic means to assure uniform actuation of the indicator irrespective of the speed of the car.

4. An electro-mechanical station indicator comprising a web bearing the names of stations, rolls complementary to the web and having tappet means exposed by unwinding of the web from the rolls, movable devices operable by said tappets when exposed, a driving connection for the rolls including a shiftable clutch member, a spring-pressed

lever on which said movable devices are mounted and movable, springs connected to said movable devices, and means connecting the said movable devices and the shiftable clutch member and including a lever in engagement with said clutch member and cables connected to the movable devices and connected with the lever, electro-mechanical means connected with said driving connection to actuate the same, and means to supply the electro-mechanical means with current at intervals in the traverse of a car and comprising automatic means to assure uniform actuation of the indicator irrespective of the speed of the car.

5. In a station indicator, the combination of a web bearing the names of stations, rolls complementary to the web and having tappet means exposed by unwinding of the web from the rolls, a driving connection to the rolls including a shiftable clutch member, and means movable by said tappets when exposed and connected with said shiftable clutch member to move the latter; the said tappet means including rod sections disposed in recesses in the peripheries of the rolls, and the web being provided adjacent to its ends with curvilinear plates adapted to rest over said recesses and rod sections, electro-mechanical means connected with said driving connection to actuate the same, and means to supply the electro-mechanical means with current at intervals in the traverse of a car and comprising automatic means to assure uniform actuation of the indicator irrespective of the speed of the car.

6. In a station indicator, the combination of a web bearing the names of stations, rolls complementary to the web and having tappet means exposed by unwinding of the web from the rolls, a driving connection to the rolls including a shiftable clutch member, and means movable by said tappets when exposed and connected with said shiftable clutch member to move the latter, with a casing body having a partition and compartments in one of which the web and rolls and the means movable by the roll-tappets are arranged; the shiftable clutch member being arranged in the other compartment, and an electric motor and shiftable connections also being arranged in the other compartment, and means to supply the electro-mechanical means with current at intervals in the traverse of a car and comprising automatic means to assure uniform actuation of the indicator irrespective of the speed of the car.

In testimony whereof, I affix my signature.

SAMUEL MITCHELL.
